UNITED STATES PATENT OFFICE

WILLIAM LONKOWSKI, OF MINEOLA, NEW YORK

BOOK MATCH HOLDER

Application filed May 2, 1930. Serial No. 449,290.

This invention relates to new and useful improvements in holders for matches manufactured in the commonly known "book form".

8 The principal object of the invention is to provide a holder for book matches wherein the matches can be retained for personal use.

Another important object of the invention is to provide a match holder of the character 10 described provided with means for urging the matches to be scratched against the usual striking surface of the match book.

Still another important object of the invention is to provide a book of match holders 15 provided with means for shielding the intact matches against ignition by the match being struck or ignited against the abrasive surface of the match book.

During the course of the following specification and claim, various other important objects of the invention will readily become apparent to the reader.

In the drawings:—

Figure 1 represents a perspective view of 25 the novel holder with a match book therein.

Fig. 2 represents a front elevational view of the holder supporting a book of matches, and showing the flap of the book in open position.

30 Fig. 3 is an enlarged longitudinal sectional view through the holder with the parts in substantially the position shown in Fig. 2.

Fig. 4 is a perspective view of the holder with the match book removed.

35 Referring to the drawings wherein like numerals designate like parts, it can be seen that the novel holder is constructed of a single sheet of metal, or in fact, any other suitable stiff springy material. This sheet 40 of material which is generally referred to by numeral 5 includes a back wall 6 provided with longitudinally extending flanges 7—7 at the longitudinal edges thereof. These flanges, which are bent laterally in the same direction, 45 extend from one end of the back wall 6 to terminate inwardly from the opposite end of the back wall. The last-mentioned end of the back wall is provided with a laterally disposed lip 8 bent in the same direction as the flanges 7—7.

The sheet of metal 5 is further constructed to provide an apron 9 which is integrally connected to the back wall 6 by the tongue 10 projecting from one end of one of the flanges 7.

55 The inner or upper edge portion of the apron 9 is provided with a channel 11 which forms a rib 12 on the inner side of the apron which is adapted to engage the butt end of the match book as in the manner shown in Fig. 3.

60 As is apparent in Fig. 3, it can be seen that the apron 9 is offset outwardly a substantial distance fixed to the portion 13, so that sufficient space will exist between the apron 9 and the striking surface 14 of the match book to accommodate a match head.

65 Briefly the match book includes the usual sheet 16 of matches which are secured at their butt ends within the confines of the folded end portion 16 of the jacket 17. As is apparent in Fig. 3, the butt end of the match book is to engage the lip 8 to the holder, to maintain the same, so that it will maintain the proper position within the holder.

70 In the use of this novel holder, the flap 17 must be first disengaged from behind the upper edge portion 13 of the apron 9, after which a match is torn from one of the match sheets 15. The head of the match is then disposed between the apron 9 and the scratching surface 14 and by pressing the apron against the match head and drawing the match in a given direction, the match head will ignite.

75 It can readily be seen that this apron 9 will guard the character of matches of the book against ignition by the inflamed match. It is of course to be understood that the apron 9 and the tongue 10 are sufficiently flexible to permit the urging of the apron against the match head to be ignited.

80 Obviously, the holder may be manufactured of any suitable material and it is to be understood that certain changes in the shape and size may be permitted without departing from the spirit and scope of the invention as claimed hereinafter.

85 Having thus described my invention what I claim as new is:—

90 A match holder of the character described

100

comprising a match book support, a scratcher plate projecting from the said support and being movable for urging a match head against the scratching surface of a match book disposed on the support, and an inwardly disposed rib on the pressure plate for engaging the match book and normally retaining the same on the support and spacing said plate from the scratching surface of the match book.

10 In testimony whereof I affix my signature.
WILLIAM LONKOWSKI.
